US0D1089102S

(12) **United States Design Patent** (10) **Patent No.:** **US D1,089,102 S**
(45) **Date of Patent:** **** Aug. 19, 2025**

(54) **CONNECTOR**

(71) Applicant: **Dongguan City Jianghan Electronics Co., Ltd**, Dongguan (CN)

(72) Inventor: **Tiejun He**, Dongguan (CN)

(73) Assignee: **Dongguan City Jianghan Electronics Co., Ltd**, Dongguan (CN)

(**) Term: **15 Years**

(21) Appl. No.: **29/894,678**

(22) Filed: **Jun. 13, 2023**

(30) **Foreign Application Priority Data**

May 30, 2023 (CN) 202330324148.0

(51) **LOC (15) Cl.** **13-03**

(52) **U.S. Cl.**

USPC **D13/133**

(58) **Field of Classification Search**

USPC ... D13/133, 146, 147, 123, 199, 139.7, 148, D13/149, 153, 154, 151, 155, 102 CPC ... H01R 4/00; H01R 4/28; H01R 4/30; H01R 4/4814; H01R 9/00; H01R 9/16; H01R 25/147; H01R 13/5205; H01R 13/5816; H01R 13/5837

(57) **CLAIM**

The ornamental design for a connector, as shown and described.

DESCRIPTION

FIG. 1 is a front, bottom, and right side perspective view of a connector, showing my new design;

FIG. 2 is a front, top, and left side perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof; and,

FIG. 8 is an enlarged bottom plan view thereof.

The broken lines shown in the drawings illustrate portions of the connector that form no part of the claimed design.

1 Claim, 8 Drawing Sheets
